UNITED STATES PATENT OFFICE.

DAVID O'CONNOR, OF ROCHESTER, NEW YORK, ASSIGNOR TO AMERICAN ROLL SCREEN COMPANY, INC., OF ROCHESTER, NEW YORK, A CORPORATION OF NEW YORK.

VENTILATOR.

Application filed April 6, 1927. Serial No. 181,532.

This invention relates to ventilators and particularly to ventilators for use in connection with windows for providing a constant well distributed supply of fresh air to rooms and for aiding in maintaining uniform temperatures in rooms while still providing an abundance of fresh air.

An object of this invention is to provide an improved ventilator by means of which air as it enters a room is satisfactorily distributed adjacent the ventilator. Another object is to provide an improved adjustable size ventilator which may be conveniently adjusted to fit windows of various sizes. Another object is to provide a ventilator structure which permits easy and rapid installation. Another object is to provide improved means for holding the various parts of the assembled ventilator in their adjusted positions. Another object is to provide an improved ventilator which is strong and durable and which is relatively inexpensive to manufacture. Other objects will be in part obvious or in part pointed out hereinafter.

The invention accordingly consists in the features of construction, combinations of elements, and arrangements of parts as will be exemplified in the structure to be herein-after described and the scope of the application of which will be indicated in the following claims.

In the accompanying drawings in which is shown one of the various possible embodiments of this invention,

Figure 1 is a front view of the assembled ventilator applied to a window casing;

Figure 2 is an end view of the ventilator in the position shown in Figure 1;

Figure 3 is an enlarged sectional view of the ventilator taken substantially on line 3-3 of Figure 1;

Figure 4 is an enlarged sectional view of the ventilator, taken substantially on line 4-4 of Figure 1;

Figure 5 is a perspective view of the central perforated body member;

Figure 6 is a perspective view of the perforated arcuate deflector; and

Figure 7 is a perspective view of one of the imperforate end members.

Similar reference characters refer to similar parts throughout the several views of the drawings.

Referring now to the drawings in detail,

there is shown a ventilator comprising a central body portion 10 which serves as a support for two end members 11, which are of substantially identical construction, and a deflector 12. The various parts of the ventilator are preferably formed of sheet metal of desirable weight punched or drilled at suitable points to form perforations. However, if desired, the entire ventilator may be constructed of heavy wire screen, or portions of it may be formed of sheet metal and other portions of wire screen. Also certain portions of the ventilator may be formed of wood, or fiber board, or other fibrous material, or any suitable sheet material.

The body member 10 is substantially channel-shaped, and it is preferably formed from a substantially rectangular blank of sheet metal the side portions of which are folded to form parallel side walls 13 projecting from the bottom wall substantially at right angles thereto. The outer end portions of the side walls or flanges 13 are folded inwardly to form grooves or channels 14 extending the entire length of the member 10. Either before or after the folding operations the bottom wall of the channel-shaped member 10 is provided with a plurality of perforations covering substantially its entire surface. The perforations may be of any desired size and shape, but it has been found that highly satisfactory results have been obtained when round holes or perforations approximately one-sixteenth of an inch in diameter spaced about the same distance apart are provided. In some instances, the size and spacing of the perforations may be determined to some extent by the climate in which they are to be used, the size of the room, and the exposure of the windows in which they are to be used.

A hook or latch member 15 is formed preferably of resilient sheet metal and has substantially parallel end portions extending substantially at right angles to the intermediate portion. One of the said end portions is spot welded or otherwise attached to the inner face of the bottom wall of the channel-shaped member 10, and the other end portion is spaced from the said member 10 and extends upwardly for engaging a wall of a groove or channel formed in the deflector 12.

The deflector 12 is also preferably formed from a substantially rectangular blank of sheet metal and provided with perforations similar to those formed in the member 10. 5 Opposite side edge portions of the member 12 are folded to provide smooth rounded edges and to reinforce the structure. The folded portions lie substantially in contact with the intermediate portion except centrally of the top portion of the deflector, where the folded portion is spaced from the intermediate portion to provide a groove or channel for the reception of the upwardly projecting end portion of the latch 15. 10 The intermediate portion of the deflector is of substantially arcuate form transversely, providing inner and outer concave and convex surfaces extending longitudinally thereof. Spring hinges 16, preferably formed of 15 resilient sheet metal, are spot welded or otherwise attached to the inner concave face of the deflector adjacent its lower edge, and have end portions which project outwardly beyond the convex face. The outwardly 20 projecting end portions of the hinge members 16 are of such length that they may lie in contact with the inner faces of the bottom wall of a groove 14, the inner face of a wall 13, and the inner face of the bottom wall of 25 the channel-shaped member 10, and they extend at such an angle with respect to the body portion of the deflector that when the deflector is applied to the member 10, with the said hinge end portions extending into 30 a groove 14, the hinges tend to hold the upper edge of the deflector spaced from the said member 10. The deflector must be forced to a position in which the latch 15 will engage a wall of the groove formed 35 adjacent its upper edge against the action of the hinges 16. The hinges 16 are preferably spaced from the ends of the deflector a greater distance than the length of the end members 11 so that when the ventilator 40 is assembled the hinges are not in contact with the said end members. 45

The deflector is preferably of the same length as the body member or support 10, and slightly more than half as wide. The 50 perforated area of the deflector extends from end to end of the deflector centrally thereof leaving relatively wide imperforate side marginal portions.

The end or attaching members 11 are imperforate except for the slots 17 formed in the end walls to receive the fastening means, and each is preferably formed from a blank of sheet metal. Each end member has two side walls 20 and an end wall 21. The end 60 walls are preferably not attached to the side walls at their ends in order that the end walls may serve in the capacity of hinge members and permit flexing of the end members during the installation of the ventilator. The side walls 20 are of such width

and so spaced apart that the end members may telescope with the member 10 with the side walls 20 projecting into the grooves 14 and in contact with the inner faces of the walls 13 forming a snug sliding fit. The side 70 walls 20 are also preferably folded upon themselves to provide two thicknesses of material and smooth outer edges for contact with the inner surfaces of the grooves 14. 75

When the ventilator is completely assembled, the lower edge of the deflector is held yieldingly in contact with the inner faces of the adjacent side walls 20 and tends to maintain the end members in their adjusted positions and prevent accidental relative movement of the various parts. Also, in the assembled ventilator a portion of the deflector intermediate its longitudinal side edges is spaced from the member 10 a greater distance than either of the side edges 80 so that a portion of the deflected air following its concave surface will pass outwardly and upwardly through the perforations therein and the remainder will be deflected toward the member 10. 85

In applying the ventilator to a window the end members are first attached to the casing in suitable positions, on opposite sides, by means of screws or other suitable fastening means passing through the slots 90 17. An end of the member 10 may then be mounted on one of the members 11 and moved to such a position that the opposite end may be mounted on the other member 11, after which the member 10 is centered. 100 The deflector is then applied with the outer ends of the hinges 16 positioned in the lower groove 14, the lower edge of the deflector engaging the upper faces of the lower side walls 20, and the outer end portion of the 105 latch 15 positioned in the groove formed in the upper side edge of the deflector. The assembled ventilator when applied to a window will have an appearance similar to the showing in Figure 1 of the drawings. If the 110 various parts of a particular ventilator are too large to permit installation as described above, the member 10 may be first mounted on the members 11 before they are secured in place on the window casing. 115

When the window is opened to the position shown in Figures 1 and 2 a portion of the air which enters a room through the perforations in the lower part of the member 10 passes through the apertures in the deflector and may settle downwardly immediately to cool and supply fresh air to the lower portion of the room adjacent the window, and the remainder is directed upwardly and tends to deflect the air entering through the 120 apertures in the upper portion of the member 10 upwardly. Regardless of the position to which the window is opened, within the limits of the member 10, the entering air 125 will be well distributed. When a strong 130

breeze is blowing out of doors, the bottom of the window frame need only be positioned at some point below the top of the deflector, and for a gentle breeze the window may be 5 raised to a position in which the lower edge of the frame is even with the top of the member 10.

From the foregoing it will be seen that there is herein provided a device which embodies the features of this invention and achieves the objects thereof. A ventilator has been provided which is of strong and durable construction; relatively inexpensive to manufacture; easy to install; dependable 15 in use; and by means of which strong drafts are avoided and fresh air entering a room may be thoroughly and evenly distributed.

As may possible embodiments may be made of the above invention, and as many 20 changes might be made in the embodiment above set forth, it is to be understood that all matter hereinbefore set forth or shown in the accompanying drawings is to be interpreted as illustrative and not in a limiting 25 sense.

I claim as my invention:

1. A ventilator comprising a perforated body member, end members adjustably mounted on said body member, and a deflector mounted on said body member and held in contact with said end members to retain said end members in their adjusted 30 positions.

2. A ventilator comprising a perforated body member, imperforate end members adjustably mounted on said body member, and a perforated deflector detachably mounted on said body member and bearing on said end members.

40 3. A ventilator comprising a perforated body member, imperforate end members adjustably mounted on said body member, and an arcuate perforated deflector detachably

mounted on said body member and bearing on said end members. 45

4. A ventilator comprising a perforated body member having a groove formed adjacent an edge thereof, a deflector, a resilient member mounted on said deflector adjacent an edge thereof and extending into the 50 groove in said body portion to form a spring hinge which normally tends to hold the opposite side edge of said deflector spaced from said body member, and means for holding said opposite side edge in a fixed position 55 relatively to said body member.

5. A ventilator comprising a channel-shaped perforated body portion, flanged end members slidably mounted on said body member with opposite flanges in contact 60 with the side walls thereof, means for confining the movement of said end members on said body members to rectilinear movement, and a deflector attached to said body portion and in contact with said end members. 65

6. A ventilator comprising a channel-shaped perforated body member having its side walls folded inwardly to form grooves adjacent the outer edges thereof, flanged end members slidably mounted on said body 70 member with opposite flanges extending into the grooves in said channel side walls, a perforated deflector mounted on said body, and resilient means mounted on said deflector and extending into a groove in a channel side 75 wall for holding said deflector in contact with said end members.

7. A ventilator comprising a perforated body member, a perforated deflector, spring members attached to the lower edge of the 80 deflector and adapted to hinge the same to the lower edge of the body member and a spring bracket attached to the body member and adapted to hold the upper edge of the deflector spaced from the body member.

DAVID O'CONNOR.
